UNITED STATES PATENT OFFICE

2,644,515

GAS BURNER HEAD WITH SECONDARY AIR FEED GROOVES

Albert J. Lampert, Walnut, and Eldon A. Merritt, South Gate, Calif., assignors to Rheem Manufacturing Company, Richmond, Calif., a corporation of California

Application December 22, 1947, Serial No. 793,092

5 Claims. (Cl. 158—114)

1

Our invention relates to gas burners and has particular reference to a burner adaptable for use in connection with, but not limited to, floor furnaces. Whereas, the preferred form of embodiment of our invention, hereinafter to be illustrated, is particularly designed for a floor furnace wherein it is desired to create large quantities of heat in a rather limited space, it is to be understood that our invention is susceptible of broader applications and that by illustrating a floor furnace burner, we do not wish to be confined to such an application.

It is among the objects of our invention to produce a highly efficient gas burner for floor furnaces which will produce large quantities of heat in a relatively small space and yet which will produce a stable flame, good flame characteristics, and a flame which is free from lifting or flashback.

In order to function effectively, raw gas, which is introduced from the supply line into the burner, must be mixed at the time of, or prior to, ignition with a certain quantity of air in order to insure sufficient oxygen for complete combustion. It has been found that air in an amount of approximately nine-tenths of a cubic foot is required for each 100 B. t. u. to be produced. For example, a heater designed to produce 1100 B. t. u. will require approximately ten cubic feet of air for complete and efficient combustion of the fuel.

In most gas burners the air is introduced in two places. Air is introduced into a jet of raw gas moving by an orifice or into the throat of a Venturi tube. The air so mixed is designated as primary air. The balance of the air necessary for complete combustion is introduced into the gas at the point of combustion and is usually designated as secondary air. The proportion between primary air and secondary air is, within limits, a matter of choice, and is usually dependent upon construction of the burner.

It is usually desired to introduce as much primary air as possible because of the uncertainty of secondary air and because a closer port spacing is thereby made possible. Certain objections arise out of the introduction of too much primary air. A mixture of too much primary air results in an explosive or a fast-burning mixture which may cause flashback if the ratio between the port depth and port area is not carefully controlled.

A further object of our invention is to provide a burner for such gas burning equipment as floor furnaces which is so constructed that a maximum port spacing can be obtained in a relatively small

burner, thereby permitting a maximum percentage of secondary air.

5 A further object of our invention is to provide a means for preventing rapid upsurge of air about the periphery of the burner to prevent lifting of the flame.

10 A still further object of our invention is to provide radially directed flame envelopes so that there will be no overlapping or commingling of the flame envelopes which would choke off secondary air.

15 In a gas burner of the type hereinafter described, which comprises a relatively long, narrow passageway, it becomes important to control the rate of flow, the turbulence of flow, and the distribution of gases entering said chamber. A further object of our invention is to provide a gas burner of the type herein described wherein the flow of gas is evenly distributed throughout the

20 interior of the passage chamber, wherein the rate of flow is substantially constant throughout its entire length of travel, and wherein the rate of flow is sufficiently low and free from turbulence to result in a stable flame.

25 Other and further objects and advantages of our invention will become apparent from the drawings and the specifications relative thereto.

In the drawings:

Figure 1 represents a plan view of a gas burner embodying our invention.

30 Figure 2 is a side elevation of the burner shown in Figure 1 having a portion thereof broken away.

Figure 3 is a bottom plan view of the burner shown in Figure 1 having a portion thereof broken away.

35 Figure 4 is an end view of the burner shown in Figure 1 taken from the right-hand side of Figure 1.

Figure 5 is a sectional view taken on line 5—5 of Figure 1.

40 The embodiment of our invention illustrated herein comprises essentially an inlet venturi, designated generally 10, a substantially rectangular housing 11 having side walls 12 and 13, a base 14 sloping downwardly towards the center, and end walls 15 and 15', all of which cooperate to define a distribution chamber 16.

The distribution chamber 16 is enclosed on the top by a transversely arcuate port outlet plate 17.

45 The venturi 10 is substantially standard construction having a gas inlet pipe with a gas inlet 20 adapted to discharge a jet of raw gas into a chamber 21 adjacent a constricted throat 22 into an expanding passage 23. As usual the raw gas 55 is discharged inwardly through the opening 20

through which a gas jet is inserted (not shown here). Primary air is aspirated into the chamber 21 and mixed with the raw gas. The chamber 21 is enclosed on the bottom by means of a plate 24 (shown in phantom) pivoted about a pivot point 25. It will readily be apparent to those skilled in the art that the rotational position of the plate 24 will determine the amount of primary air aspirated into and mixed with the raw gas. The passage 23 is in communication with the distribution chamber 16 at its lowermost point, designated 28.

Gas directing baffles 30 and 31 are formed as an integral part of the interior of the walls 13 and 12, respectively, and extend inwardly approximately one-third of the distance between the walls 13 and 12 and are positioned immediately super-adjacent the inlet from passage 23. The baffles 30 and 31 act to prevent too rapid a rise of the gas in the central portion of the burner which would result in an overloading of the ports in the center of the burner and starvation of the ports at the outer extremes. The flow of gas is both retarded and spread outwardly by these baffles 30 and 31.

Vertically disposed ribs 32 and 33 extend between the base 14 and the baffles 30 and 31 at a position disposed outwardly from the center line of the burner with respect to the Venturi entrance. The purpose of the vertical ribs 32 and 33 is as follows: As the stream of air and gas mixture enters through the venturi 10 and changes directions in entering the chamber through passageway 23, the gas still has a slight momentum towards the far end of the burner. The ribs 32 and 33 exert a retarding influence on the flow of gas thereby effecting a more equal distribution. Such an arrangement permits the use of a venturi which is disposed parallel with the distribution chamber and in relatively close proximity thereto.

The transversely arcuate, port outlet plate 17 is formed with a plurality of transversely disposed undercut sections or grooves 40 having chordal bottoms and disposed in staggered relation on opposite sides of the longitudinal center line of said plate 17, thereby defining a plurality of raised arcuate sections or ridges 41 which are also in staggered relation on opposite sides of the longitudinal center line of said plate 17. A plurality of ports 42 are drilled at spaced intervals along a longitudinal center line. It is to be noted that the position of the ports on the longitudinal center line are such that no port is in alignment with the center line of the raised sections 41. The staggering or offsetting of opposite ridges 41 avoids a snuffing action which would otherwise follow from symmetrical placement of the ridges. Burning of the gas at any one ridge 41 produces a fan-like area of combustion in which the flowing gases in the outer edges of the fan tend to turn back down in whirlpool fashion and return to the level at which they were first burned. If the ridges 41 on opposite sides of the burner were to be placed in line, it is readily seen that burning at one of the ridges would interfere with combustion at the other ridge, and vice versa. Thus the staggering or offsetting of opposite ridges minimizes this cross interference due to the doubling back of the combustion products. Each of the sections 41 is drilled with a plurality of ports 43. The ports 43 are drilled radially from a common center point. Such center point is the center of curvature of the transverse radius of the plate 17.

The principal purpose of drilling the ports 42 and 43 so that they emanate from a common center point should be readily apparent in that such an arrangement results in a wider spacing 5 of the ports at the outer or discharge end and also results in a fanning-out of the flame envelopes.

Thus it will be seen that we have provided a burner with a plurality of ports, each of which 10 is freely exposed on at least two sides to secondary air and which are arranged at a maximum spacing to permit travel of secondary air between the flame envelopes thereby resulting in a more efficient combustion of fuel. The undercut sections 40 permit secondary air to enter 15 from the sides of the burner, thereby completely supplying secondary air to every individual port.

It will be noted in Figure 5 that the chord of the arcuate section 17 is less than the outside width of the burner thereby defining a ledge or shoulder 50. The shoulder 50 acts to interrupt the upward flow of air along the side walls 12 and 13, thereby effectively preventing lifting of the flame caused by an upsurge of secondary air.

It will be noted in Figure 2 that lugs or legs 51 and 52 depend from the side wall 13 of the burner and that mounting brackets 53 and 54 extend outwardly from the ends 15 and 15'. Such 30 elements constitute no part of the invention herein, but as will be understood by those skilled in the art, are provided as a convenient means for mounting the burner in the proper or desired position.

As an example of a modification which we feel comes within the scope of our invention, the venturi 10 can be disposed at right angles to the distribution chamber 16 rather than parallel as shown. In the event that the venturi 10 is disposed at right angles, the vertical ribs 32 and 33 will not be necessary as it is understood that the vertical ribs 32 and 33 are adapted to restrict the flow of gas from the venturi into the left-hand end (Figure 3) of the mixing chamber 16. 40 It will readily be understood that in the embodiment shown in Figure 3 the gases, upon entering the distribution chamber, will still possess a slight momentum towards the left-hand side (Figure 3) of the distribution chamber, which would thereby result in starvation of the ports at the other end. One of the important features of our invention lies in the use of baffles to utilize the distribution of gases throughout the distribution chamber.

As another example of what we would consider equivalent of our invention, would be a construction whereby undercut sections 40 instead of being undercut could be a part of the original casting pattern and which could also result in a raised bead extending longitudinally in the center of the arcuate section 17. It will readily be understood that the important feature we wish to stress is the fact that the radially drilled ports 43 are so situated that every port is raised above the burner and is freely open to secondary air on at least two sides.

While we have herein shown and described our invention in what we have conceived to be the most practical and preferred embodiment, it is 70 recognized that departures may be made therefrom within the scope of our invention, which is not to be limited to the details disclosed herein, but it is to be accorded the full scope of the claims.

Having described our invention, what we claim 75 as new and desire to secure by Letters Patent is:

1. A gas burner head having a substantially greater length than width and defining a rectangle in plan, comprising a bottom, side walls and a top defining a distribution chamber decreasing in cross-section outwardly toward the ends thereof, said top being transversely arched and arcuate defining a segment of a cylinder having an apex of said arcuate section defining a longitudinal centerline substantially midway between the sides thereof, said top being formed with a plurality of apertures in spaced relation along said longitudinal centerline defining gas discharge ports and a plurality of apertures in spaced relation along a plurality of transverse lines extending from said centerline outwardly, adjacent transverse lines being in staggered relation on opposite sides of said centerline, the extent of such staggering being at least equal to the span of an aperture, said top also being formed with a transverse groove having a chordal bottom between each of said transverse lines of discharge ports, thereby permitting the free access of secondary air to each side of each of said burner ports.

2. A gas burner head having a substantially greater length than width, comprising a bottom, side walls and a top defining a distribution chamber decreasing in cross-section outwardly toward the ends thereof, said top being transversely arched and arcuate in section and being symmetrical in its plan view having an apex of said arcuate section defining a longitudinal centerline substantially midway between the sides thereof, said top being formed with a plurality of apertures in spaced relation along said longitudinal centerline defining gas discharge ports and a plurality of apertures in spaced relation along a plurality of transverse lines extending from said centerline outwardly, adjacent transverse lines being in staggered relation on opposite sides of said centerline, the extent of such staggering being at least equal to the span of an aperture, said top also being formed with a transverse groove having a chordal bottom between each of said transverse lines of discharge ports, thereby permitting the free access of secondary air to each side of each of said burner ports.

3. A gas burner head having a substantially greater length than width, comprising a bottom, side walls and a top defining a distribution chamber decreasing in cross-section outwardly toward the ends thereof, said top being transversely arched and arcuate in section and symmetrical in its plan view having an apex of said arcuate section defining a longitudinal centerline substantially midway between the sides thereof, said top also being relatively narrower than the body of said burner head, thereby defining a peripheral shoulder between said body and said arcuate top, said top being formed with a plurality of apertures in spaced relation along said longitudinal centerline defining gas dis-

charge ports and a plurality of apertures in spaced relation along a plurality of transverse lines extending from said centerline outwardly, adjacent transverse lines being in staggered relation on opposite sides of said centerline, the extent of such staggering being at least equal to the span of an aperture, said top also being formed with a transverse groove having a chordal bottom between each of said transverse lines of discharge ports, thereby permitting the free access of secondary air to each side of each of said burner ports, and baffle means disposed in said distribution chamber adapted to cause an even distribution of combustible gases entering therein.

15 4. A gas burner comprising an elongate housing having a transversely arched and arcuate top, a pair of generally horizontal ledges bordering said top, generally vertical sides, a plurality of substantially radial ports in said top spaced along 20 a central longitudinal line and along transverse lines on each side of said central line, adjacent transverse lines being staggered on opposite sides of said central line, the extent of such staggering being at least equal to the span of an aperture, 25 and a plurality of grooves having chordal bottoms disposed between said transverse lines so as to situate said transverse lines on ridges raised from the top proper.

5. A gas burner comprising an elongate housing having a transversely arched and arcuate top, generally vertical sides, a plurality of substantially radial ports in said top spaced along a central longitudinal line and along transverse lines 30 on each side of said central line, adjacent transverse lines being staggered on opposite sides of said central line, the extent of such staggering being at least equal to the span of an aperture, and a plurality of grooves having chordal bottoms disposed between said transverse lines so as to situate said transverse lines on ridges raised from the top proper.
